UNITED STATES PATENT OFFICE.

CHARLES MELROSE, OF SAN FRANCISCO, CALIFORNIA.

DEMONSTRATING-MODEL.

No. 800,000.

Specification of Letters Patent.

Patented Sept. 19, 1905.

Application filed October 12, 1904. Serial No. 228,234.

To all whom it may concern:

Be it known that I, CHARLES MELROSE, a citizen of the United States of America, residing at San Francisco, county of San Francisco, and State of California, have invented certain new and useful Improvements in Demonstrating-Models; and I hereby declare the following to be a full, clear, and exact description of the same, reference being had to the accompanying drawings, forming a part of this specification.

This invention relates to demonstrating-models to illustrate by certain adjustments the mode of operating and the functions of distributing-valves for steam-engines actuated by what is technically called "link-gearing," as hereinafter described, and illustrated by diagrammatic drawings forming a part of this specification.

My invention consists in patterns or models of the various operating parts of a steam-engine connected and operative to show the movements and relation of the various parts in their relative positions, the whole made preferably of thin metallic plates mounted on a plate or other suitable plane surface convenient to handle and durable in its nature.

The objects of my invention are educational, to instruct students and apprentices in the art of designing, operating, and making valve-gearing, and to enable practical steam-engineers to perform the various adjustments in valve-gearing in a correct manner.

Referring to the drawings, Figure I is a plan view of a demonstrating-model with simple link-motion constructed and arranged according to my invention. Fig. II is an edge view of the device shown in Fig. I. Fig. III is a plan view of the same general features as Fig. I, but with the link suspended in a manner that permits adjustment to compensate the angularity of the connecting-rod; and Fig. IV, an edge view of the device shown in Fig. III with screw 24 omitted.

The several parts are indicated by reference-numerals as follows.

1 represents the engine-cylinder; 2, the piston; 3, the piston-rod; 4, the cross-head; 5, the cross-head guide; 6, the connecting-rod; 7, the crank-wheel; 8 and 9, the eccentrics; 10 and 11, eccentric-rods; 12, the link; 13, the distributing or slide valve; 14, the valve-rod; 15, a lever that reverses the motion of the link and valve relatively; 16 and 17, devices for suspending and adjusting the link; 19, a plate on which the parts are mounted;

20 and 21, induction ports or passages; 22, the eduction-port.

All the various joints in the model requiring adjustment are movable and provided with slots and clamping-screws as follows: the eccentrics 8 and 9 by the screw 23, the link in Fig. I by the screw 24, the valve 13 by the screw 25, the eccentric-rod by the screws 26, the link-hanger by the screw 27.

The crank-wheel 7 is marked, as shown, at ninety degrees of arc to indicate dead-centers and quarters of stroke; also, may have further divisions, if required. The cross-head slides 5 and cylinder 1 have divisions or indication-points marked thereon, such as are required in practice to determine, with the adjustments, the following functions: the effect of outside and inside lap of distributing-valves; steam distribution as affected by the angularity of the connecting-rod; points of admission and cut-off in respect to the position of the piston and stroke; expansion and compression so far as controllable by a single distributing-valve; the position or angle of advance for eccentrics; the effect of suspending a link outside of its central arc or offsetting the "saddle-pin," as it is technically termed; adjustment of the link in respect to crank-shaft center; also, various other problems connected with steam distribution by a single valve.

It will be obvious that the slide-valve 13 can be arranged for outside or inside admission of steam, the lap being provided for accordingly; also, that the action is the same whatever be the form of the valve-faces.

In operating the adjustments are permitted by the several movable joints, the effect being obvious except as to the screw 27 in Figs. III and IV, dealing with the angularity of the connecting-rod. This latter adjustment produces a circular movement of the body of the link 12 on an arc the radius of which is the distance of the pivot or screw 27 from the central line of the link 12, but modified by the position of the link, and as a graphic or computed problem is intricate, but can be clearly demonstrated by the present model.

The eccentrics 8 and 9 are loosely mounted on the crank-shaft and independently adjustable about the center thereof, so as to be readily adjusted to any desired position relatively and are clamped by the screw 23 when adjusted. This forms an important feature of my invention and enables various experiments to be made in demonstrating.

Having thus explained the nature and objects of my invention, what I claim as new, and desire to secure by Letters Patent, is—

The herein-described model for educational use, consisting of thin plates representing the various parts of a link-motion steam-engine, movably and adjustably connected together, the eccentrics being independently revoluble about the crank-shaft center, with means for

clamping them in different relative positions 10 while revoluble, substantially as specified.

In testimony whereof I have signed my name to this specification in the presence of two subscribing witnesses.

CHARLES MELROSE.
